UNITED STATES PATENT OFFICE.

ALFRED NORTON GOLDSMITH, OF NEW YORK, N. Y., ASSIGNOR, BY MESNE ASSIGNMENTS, TO RADIO CORPORATION OF AMERICA, A CORPORATION OF DELAWARE.

METHOD AND APPARATUS FOR TRANSMITTING SUSTAINED WAVE SIGNALS.

Application filed July 29, 1919. Serial No. 314,031.

To all whom it may concern:

Be it known that I, ALFRED N. GOLDSMITH, a citizen of the United States, and a resident of the borough of Manhattan, city, county, 5 and State of New York, have invented certain new and useful Improvements in Methods and Apparatus for Transmitting Sustained Wave Signals, of which the following is a specification accompanied by 10 drawings.

This invention relates to radio signaling, but more particularly to an improved method and apparatus of tone transmission from a sustained wave generator. Since sustained wave transmitters produce signals 15 consisting of constant amplitude radio frequency current, such signals are inaudible, (or practically so) in a receiving system having the usual rectifying detector, such as 20 a crystal or vacuum tube. Notwithstanding this fact, transmitters on ship board which may be called upon for distress signals, are compelled by law to be capable of radiating a signal wave of such character that it is 25 possible of reception and detection in such a simple detector of a receiving set.

It is accordingly highly desirable and even necessary to provide a method of controlling and modifying the sustained wave radiation 30 of an arc, alternator, oscillating vacuum tube, or other sustained wave transmitter so that periodically modulated radiation is capable of being produced, that is, the amplitude of the radiation should be periodically 35 varied at audio frequency.

In my copending application Serial #313,691, I have disclosed a method and apparatus for receiving sustained wave signals in which the energy is modulated by periodically 40 varying the mutual inductance between primary and secondary coils acting as a transformer in the circuits. In one of the preferred forms of the apparatus there disclosed the modulator consists of a shield of 45 conducting material which is interposed and withdrawn between the primary and secondary transformer coils, thereby varying the mutual field of said coils and producing an audio frequency cycle in the circuits.

50 I have found that this method of modulation may be advantageously applied to apparatus for transmitting from a sustained wave generator, and by this means the desired results, with tone transmission are ob-

tained. For example, if the arc circuits and 55 the antenna circuit of a transmitting station are periodically coupled and decoupled by means of a suitable modulator to be described, the antenna radiation has the desired tone character. The antenna and primary inductances of this modulator, together with the conducting shield which may be a rotator, are preferably made correspondingly heavier than would be suitable 60 for receiving work.

Preferred forms of transmitting apparatus for carrying out the method are illustrated in the accompanying drawings in which—

Fig. 1 is a diagrammatic representation of 70 circuits and apparatus for carrying out the invention;

Fig. 2 is a detail side view of the rotator of the modulator;

Fig. 3 is a diagrammatic view of a modification of the apparatus;

Fig. 4 is a detail side view partly broken away of the rotator in Fig. 3 showing the relative arrangement of the coils;

Fig. 5 is a diagrammatic view of another 80 modification; and

Fig. 6 is a detail view partly broken away of the rotator in Fig. 5 showing the relative arrangement of the coils.

Referring to the drawings and at first 85 more particularly to Figs. 1 and 2, A represents the antenna of a transmitting station, grounded at B and having a variable loading coil C and antenna coupling coil D. A transmitting key C' may be provided in any 90 suitable location as shown. The primary circuit E includes the primary coupling coil F, the variable condenser G, and in this instance the arc H fed from a suitable source of direct current, as a generator J. Choke coils 95 and other auxiliary equipment in the direct current leads are omitted for the sake of simplicity.

The coupling coils D and F forming a 100 part of the modulator K are preferably arranged substantially as indicated, which has been found to be a practical working arrangement, although they may be of any desired shape or construction. The shield of the modulator which is operatively connected to be periodically or intermittently interposed between the coils D and F, is shown in this instance as a toothed copper disk L,

which may or may not be grounded as indicated at O. The disk L is conveniently mounted on the shaft P of a suitable motor Q which may conveniently be of variable speed, in such position that the teeth R pass between the coils D and F and these teeth are preferably of proper size and dimensions to substantially completely cover the aperture of the coils when registering therewith, 10 as shown in side view in Fig. 2.

As the modulator disk L is rotated between the coupling coils D and F, the mutual inductance between the coils is periodically varied, in effect coupling and decoupling the coils. By choosing a proper number of teeth on the disk or rotator L and a suitable running speed, radiation of any desired tone character is produced and a note of any desired pitch may be obtained 20 in the telephones at a receiving station.

In those instances in which it is desirable to keep substantially constant load upon the radio frequency sustained wave generator, the modification shown in Figs. 25 3 and 4 may be used. In said figures the same rotator L acts to couple and decouple the coils D and F and also, although independently, the coils S and T, one of which, as the coil S is connected in an artificial 30 antenna or absorbing circuit U having substantially the same constants as the actual antenna A, and the other coil T is connected in the primary circuit E'. These coils S and T are arranged opposite each other as 35 shown, but so spaced relatively to coils D and F, as shown in side view in Fig. 4, that the separation between the respective pairs of coupling coils is an odd number of times the width of a tooth R on the rotator L. 40 With this construction and arrangement, as coils D and F are periodically and progressively coupled, the coils S and T will be periodically progressively but inversely decoupled. The arc H will always be coupled 45 either to the real antenna A or the artificial antenna U, and as the arc is coupled to one of these antennæ, it is synchronously decoupled from the other, so that the total load on the sustained wave generator remains substantially constant. 50

In practicing my method with the apparatus shown in Figs. 1 and 3, the wave length or frequency of the radiated wave may be slightly altered at audio frequency, 55 due to slight variations in inductance in the oscillating circuit of the arc, caused by the introduction of the teeth of the rotator L in the field of the coils. In the modification shown in Fig. 5, means are provided for 60 maintaining the total inductance of the circuits substantially constant. In Fig. 5, auxiliary coils V and W in the antenna and primary circuits respectively, are so arranged that the rotator L passes through their field, 65 but these auxiliary coils are not coupled to

each other. Coils D and V in the antenna circuit are made equal to each other, as are also coils F and W in the primary circuit E².

One mode of arranging the coils relative to the rotator L is indicated in side view in Fig. 6. Coils D and F as in Fig. 1 are arranged opposite each other, while coils V and W are arranged out of the field of each other and of coils D and F. These auxiliary coils V and W are so placed that when a tooth R of the rotator L lies squarely between coils D and F air spaces are directly opposite coils V and W, and vice versa. As the inductance of coils D and F is diminished by the introduction of a tooth R between them, the inductance of coils V and W is increased by an appreciable amount in synchronism therewith. The total inductance of coils D and V remains unchanged, as also does the total inductance of coils F and W, and the radiation, though variable in amplitude will not change in wave length. 75

Obviously the features shown in Figs. 3 and 5 may be combined in one system in any suitable and convenient manner well understood by those skilled in the art, so that both the total inductance of the circuits and the load on the generator may be maintained substantially constant. 90

I claim and desire to obtain by Letters Patent the following:

1. In radio signaling, the method of transmitting sustained wave signals, which consists in intermittently shielding the secondary from the primary coils acting as a transformer in the transmitting circuits, at a rate capable of producing radiation of tone character. 100

2. In radio signaling, the method of transmitting sustained wave signals, which consists in intermittently electro-magnetically shielding the secondary from the primary of a transformer in the transmitting circuits, at a rate capable of producing radiation of tone character. 105

3. In radio signaling, the method of transmitting sustained wave signals, which consists in periodically varying the mutual inductance between coupling coils acting as a transformer in the primary and secondary transmitting circuits at a rate capable of producing radiation of tone character. 115

4. In radio signaling, the method of transmitting sustained wave signals, which consists in modulating the supplied energy by periodically varying the mutual field of coupling coils acting as a transformer in the primary and secondary transmitting circuits at a rate capable of producing radiation of tone character, while maintaining substantially constant load on the source of sustained waves. 120

5. In apparatus for transmitting sus- 130

- tained wave signals, the combination of transmitting circuits, and means for modulating the supplied energy comprising coupling coils acting as a transformer in the transmitting circuits, and means for intermittently shielding the secondary from the primary coupling coil, at a rate capable of producing radiation of tone character.
6. In apparatus for transmitting sustained wave signals, the combination of transmitting circuits, and means for modulating the supplied energy comprising coupling coils acting as a transformer in the transmitting circuits, and means for intermittently electro-magnetically shielding the secondary from the primary coupling coil, at a rate capable of producing radiation of tone character.
7. In apparatus for transmitting sustained wave signals, the combination of transmitting circuits, and means for modulating the supplied energy comprising coupling coils acting as a transformer in the transmitting circuits, and means for intermittently interposing a conducting medium between the coupling coils, at a rate capable of producing radiation of tone character.
8. In apparatus for transmitting sustained wave signals, the combination of transmitting circuits, and means for modulating the supplied energy comprising coupling coils acting as a transformer in the transmitting circuits, and means for intermittently interposing a short circuited secondary between the said coupling coils, at a rate capable of producing radiation of tone character.
9. In apparatus for transmitting sustained wave signals, the combination of transmitting circuits, and means for modulating the supplied energy comprising coupling coils acting as a transformer in the transmitting circuits, and means for periodically inserting and withdrawing a shield of conducting material between said coupling coils, at a rate capable of producing radiation of tone character.
10. In apparatus for transmitting sustained wave signals, the combination of transmitting circuits, and means for modulating the supplied energy comprising coupling coils acting as a transformer in the transmitting circuits, and means for periodically varying the mutual inductance between said coupling coils at a rate capable of producing radiation of tone character, and means for maintaining the total inductance of the transmitting circuits substantially constant.
11. In apparatus for transmitting sustained wave signals, the combination of transmitting circuits, and means for modulating the supplied energy comprising coupling coils acting as a transformer in the transmitting circuits, and means for periodically varying the mutual field of said coupling coils at a rate capable of producing radiation of tone character; and means for maintaining the total inductance of the transmitting circuits substantially constant, thereby producing radiation of tone character.
12. In apparatus for transmitting sustained wave signals, the combination with a source of sustained waves, transmitting circuits, and means for modulating the supplied energy comprising coupling coils acting as a transformer in the transmitting circuits, means for periodically varying the mutual inductance between said coupling coils at a rate capable of producing radiation of tone character, and means for maintaining substantially constant load on the source of sustained waves.
13. In apparatus for transmitting sustained wave signals, the combination of a source of sustained waves, transmitting circuits, and means for modulating the supplied energy comprising coupling coils acting as a transformer in the transmitting circuits, means for periodically varying the mutual field of said coupling coils, and means for maintaining substantially constant load on the source of sustained waves.
14. In radio signaling, the method of tone transmission from a sustained wave generator, which consists in alternately dissipating the supplied energy outside the signaling circuits and releasing the supplied energy into the antenna circuit at a rate capable of producing radiation of tone character.
15. In radio signaling, the method of tone transmission from a sustained wave generator, which consists in alternately dissipating the supplied energy outside the signaling circuits and releasing the supplied energy into the antenna circuit at a rate capable of producing radiation of tone character, while maintaining the total inductance of the circuits substantially constant.
16. In radio signaling, the method of tone transmission from a sustained wave generator, which consists in periodically absorbing and releasing the supplied energy at a rate capable of producing radiation of tone character, while maintaining substantially constant load on the sustained wave generator.
17. In radio apparatus for tone transmission of sustained oscillations, the combination of a sustained wave generator, transmitting circuits, and means for alternately dissipating the supplied energy outside the signaling circuits and releasing the supplied energy at a rate capable of producing radiation of tone character.
18. In radio apparatus for tone transmission of sustained oscillations, the combination of a sustained wave generator, transmitting circuits, and means for periodically

- absorbing and releasing the supplied energy at a rate capable of producing radiation of tone character, and means for maintaining the total inductance of the circuits substantially constant.
19. In radio apparatus for tone transmission of sustained oscillations, the combination of a sustained wave generator, transmitting circuits, and means for periodically absorbing and releasing the supplied energy at a rate capable of producing radiation of tone character, and means for maintaining substantially constant load on the sustained wave generator.
- 15 20. In radio signaling, the method of tone transmission from a sustained wave generator, which consists in periodically absorbing and releasing the supplied energy at a rate capable of producing radiation of tone character, while maintaining the total inductance of the circuits and the load on the sustained wave generator substantially constant.
21. In radio apparatus for tone transmission of sustained oscillations, the combination with an antenna, of a sustained wave generator, transmitting circuits, means for periodically absorbing and releasing the supplied energy at a rate capable of producing radiation of tone character, means for maintaining the total inductance of the circuits substantially constant, and means for maintaining substantially constant load on the sustained wave generator.
- 35 22. In apparatus for transmitting sustained wave signals, the combination with transmitting circuits, coupling coils therein and a member having a plurality of conducting projections movable through the mutual field of said coils at a frequency corresponding to that of an audible tone.
23. In apparatus for transmitting sustained wave signals, the combination of transmitting circuits, coupling coils therein and a member having a plurality of conducting projections rotatable through the mutual field of said coils at a frequency corresponding to that of an audible tone.
- 45 24. In apparatus for transmitting sustained wave signals, the combination of transmitting circuits, coupling coils therein and a flat plate having a plurality of conducting projections movable through the mutual field of said coils at a frequency corresponding to that of an audible tone.
- 50 25. In apparatus for transmitting sustained wave signals, the combination of transmitting circuits, coaxial coupling coils therein and a member having a plurality of conducting projections rotatable about an axis parallel to the axis of the coils through the mutual field of said coils at a frequency corresponding to that of an audible tone.
- 55 26. In apparatus for transmitting sus-
- tained wave signals, the combination of transmitting circuits, a pair of coupling coils therein closely adjacent to each other and a member having a plurality of conducting projections movable through the mutual field of said coils at a frequency corresponding to that of an audible tone.
27. In apparatus for transmitting sustained wave signals, the combination with transmitting circuits, a pair of coupling coils therein closely adjacent to each other and a flat conducting plate having a plurality of teeth rotatable between the coils at a frequency corresponding to that of an audible tone.
28. In apparatus for transmitting sustained wave signals, the combination of transmitting circuits, coupling coils therein and a member having a plurality of conducting projections movable between the coils, said coils and projections having areas of similar magnitude.
29. In apparatus for transmitting sustained wave signals, the combination of transmitting circuits and means for modulating the supplied energy comprising coupling coils in the antenna and transmitting circuits and a grounded short circuited secondary adapted to be moved through the mutual field of said coils at a frequency corresponding to that of an audible tone.
30. In apparatus for transmitting sustained wave signals, the combination of transmitting circuits, coupling coils therein, an inductance coil in the antenna and an inductance coil in the transmitting circuit, said inductances being in decoupled relation and a member having a plurality of conducting projections adapted to be alternately interposed at a frequency corresponding to that of an audible tone in the mutual field of the coupling coils and the self fields of the inductance coils.
31. In apparatus for transmitting sustained wave signals, the combination of transmitting circuits, coupling coils therein, a second pair of coupling coils, one of which is connected in the transmitting circuits and the other in a loading circuit and a member having a plurality of conducting projections adapted to be alternately interposed at a frequency corresponding to an audible tone in the mutual fields of said pairs of coupling coils, whereby the antenna and loading circuit alternately absorb the supplied energy.
